CLAIM

We claim the ornamental design for a cross flow electrodialysis cassette, as shown and described.

DESCRIPTION

FIG. 1 is an isometric view from top;

FIG. 2 is a plan view from top;

FIG. 3 is a plan view from bottom;

FIG. 4 is a plan view from front;

FIG. 5 is a plan view from back;

FIG. 6 is a plan view from left; and,

FIG. 7 is a plan view from right.
